UNITED STATES PATENT OFFICE.

MARQUIS W. STEVENS, OF LINDEN, MICHIGAN, ASSIGNOR TO M. L. STEVENS,
OF SAME PLACE.

PLATFORM-GEAR FOR WAGONS.

SPECIFICATION forming part of Letters Patent No. 248,960, dated November 1, 1881.

Application filed March 23, 1881. (No model.)

To all whom it may concern:

Be it known that I, MARQUIS W. STEVENS, of Linden, in the county of Genesee and State of Michigan, have invented an Improvement 5 in Wagons, of which the following is a specification.

The nature of my invention relates to certain new and useful improvements in attachments to platform-gears for wagons by means 10 of which a greater flexibility of the wagon is obtained, so that as one of the wheels passes over an obstruction the wagon-body will not be tilted with the elevation of one end of the axle, but will preserve its position parallel with the 15 plane of the earth.

My invention, therefore, consists in the peculiar construction, combination, and operation of devices, by means of which and the circle of a platform-gear the above-mentioned 20 result will be obtained.

Figure 1 is a perspective view of the circle formed on top of platform-gears with my improved radially-sliding head-blocks attached thereto. Fig. 2 is a perspective view of the 25 arched slide-base of my improved head-block detached. Fig. 3 is a like view of my cap-slide detached. Fig. 4 is a longitudinal vertical section of the same, showing also the means of connecting it to a wagon. Fig. 5 is a vertical cross-section of the same.

In the accompanying drawings, which form a part of this specification, A represents the circle or "fifth-wheel," always forming part of the platform-gear of a wagon. To the top of 35 this circle, at equal distances fore and aft of the center thereof, I secure the metallic arches B, which form the base-slides of my improved head-blocks. At each side the base of the arches are the rigid stops a.

40 C are the cap-slides, flat on top, and with bottom faces curved upon the same radius as the curves of the arch, and provided with

flanges b, one on each side, to embrace the sides of the arches. The tops of the slides are recessed, the bottom of the recess having a 45 curve of the same radius above mentioned and a rectangular slot, c, through which and the arch a bolt, d, passes to hold the arches and cap-slides in their relative position without interfering with the free lateral and radial movement of the latter upon the former. 50

In Fig. 4 may be seen the manner of connecting the device with the box and lower platform of a wagon, F representing one of the bolsters or cross-bars fastened to the box G 55 for receiving the cap-slides C, and D the lower part of the fifth-wheel securely fastened to the frame E of a wagon. It will readily be seen that by the employment of these slides the elevation of one end of the axle will not tilt the 60 wagon-box resting upon the slides, as the tendency in this direction is counteracted by the sliding radial movement of the cap-slides.

One of these arches and cap-slides may be employed, with splendid effect, as the head- 65 block of a wagon with elliptic springs.

What I claim as my invention is—

1. In combination with a wagon platform-gear, the arched base B, having a central hole for receiving the bolt d, and provided with 70 stops a, the curved slotted cap-slide C, provided with side flanges, b b, the bolt d, and the side flanges b b, substantially as and for the purpose specified.

2. In combination with a wagon platform-gear and king-bolt, the arched bases B, having rigid stops a, curved cap-slides C, and bolts d, substantially as and for the purpose specified. 75

MARQUIS W. STEVENS.
